UNITED STATES PATENT OFFICE.

GUSTAV KARL HENNIG, OF BÖHLITZ-EHRENBURG, NEAR LEIPZIG, GERMANY, ASSIGNOR
TO THE FIRM OF LUDWIG HUPFELD AKTIENGESELLSCHAFT, OF BÖHLITZ-EHRENBURG, NEAR LEIPZIG, GERMANY.

PNEUMATICALLY-PLAYED MUSICAL INSTRUMENT.

1,223,048.

Specification of Letters Patent.

Patented Apr. 17, 1917.

Application filed October 27, 1914. Serial No. 868,865.

To all whom it may concern:

Be it known that I, GUSTAV KARL HENNIG, a subject of the King of Saxony, residing at 1 Bielastrasse, Böhlitz-Ehrenberg, near 5 Leipzig, Germany, have invented certain new and useful Improvements in and Relating to Pneumatically-Played Musical Instruments; and I do hereby declare the following to be a full, clear, and exact description 10 of the invention.

This invention relates to accentuating or emphasizing apparatus for pneumatically played musical instruments of the kind comprising a number of throttling devices. The 15 various throttling devices of emphasizing apparatus according to this invention are directly connected in parallel to the main suction chamber of the playing apparatus. The throttling devices may or may not be 20 dependent upon each other. The wind pressures produced by the various throttling devices are relative to the wind pressures produced by the main suction chamber.

In the case of throttling devices which 25 are dependent upon each other the arrangement may be such that a still greater wind pressure than that normally produced by the particular adjustment of the throttling mechanism for the time being, may be produced for the purpose of special emphasis. Moreover, in some cases the wind pressure produced by one of the throttling devices may be varied as may be desired, independently of the wind pressure produced by the 30 other throttling devices.

Figure 1 of the accompanying drawing 35 diagrammatically illustrates one construction of emphasizing apparatus according to my invention, and

40 Fig. 2 is a view similar to Fig. 1, illustrating another construction.

Referring to Fig. 1, *a* is the suction chamber for producing ordinary wind, and has a double valve whose upper large valve plate 45 *b* controls communication to a chamber *3*, provided with a connection *4* leading to the customary suction devices, not shown.

The suction chamber *a* communicates with a plurality of tone controlling chambers, 50 (there being two such chambers *f* and *g* shown in Fig. 1,) by means of suitable connections *8* and *9* respectively, whose inlet openings *d* and *e* are more or less closed or

controlled by slide valves *b* and *c* respectively.

55

The valve *b* is mounted on an actuating rod *b'* supported in a stationary bearing *11*, through which the rod is slidable. The rod *b'* is pivoted at *12* to a lever *b''* whose lower end is pivoted to one end of a link *13*, the other end of which link is pivoted at *14* to the movable member *h''* of an exhausting bellows *h*.

The bellows *h* is connected by an exhaust conduit *h'* to an extension *f'* of the tone 65 modulating chamber *f*.

The valve *c* which controls the tension in suction chamber *g* is provided with a valve rod *c'* which is pivotally connected at 70 *15* to a lever *c''*. The lower end of this lever *c''* is pivoted to one end of a link *16* whose other end is pivoted to the movable member *i''* of an exhausting bellows *i* that has communication with the interior of the tone modulating chamber *g* through a port 75 or equivalent connection *i'*. The upper end of lever *c''* is connected by a link *c''* to lever *k'* provided with a handle *17*.

The upper end of lever *b''* for actuating the valve *b* is also pivotally connected by 80 a link *b''* to this same lever *k'*.

The lever *k'* is pivoted to one end of a rod *l* whose other end is pivotally connected to the movable member *n'* of the smaller chamber *n* of an unsymmetrical double pneumatic *n o*. The rod *l* is operated either by the double pneumatic or by hand in a customary manner, as indicated by the hand lever *17*.

The double pneumatic *n o* has a middle 90 member *18* that is movable and has a port or passage *19* connecting the larger chamber *o* with the smaller chamber *n*.

The stationary member *20* of the double pneumatic *n o* has two conduits *21* and *22*, 95 the one *22* entering the stationary member *20* directly opposite the port *19* and serving primarily for controlling the wind in the smaller chamber *n*, while the other conduit *21*, which is displaced therefrom, serves primarily for controlling the wind in the larger chamber *o*.

The chambers *n* and *o* are controlled by the note sheet by any suitable or well known devices, and I have illustrated by way of 105 example the conduit *21* leading to a valve

chamber 23 having a port 24 leading to the atmosphere, and a port 25 leading to an exhaust chamber 26.

A valve p has a stem 27 seating on a membrane 28 whose upper side is under the action of the exhaust in chamber 26 and whose lower side has a small bleeder passage 29, also connecting the under side of the membrane with the chamber 26.

10 The space below the membrane 28 is connected by a tube 30 with a tracker bar T. The conduit 22 is controlled by a like valve q operated through a tube 31, also connected to the tracker bar T. Another like valve t controlled through a tube 32 connected to a tracker bar will be hereinafter referred to in connection with the element it controls.

20 These three valves are all alike and of well known construction, so that their operation need not be specifically described, and they all operate in connection with the same exhaust chamber 26.

25 This chamber 26 is connected by a conduit 33 with the main wind chamber a or is otherwise exhausted to place tension in chamber 26.

30 The movable member h^2 of the exhaust bellows h is connected to a spring h^3 under tension secured to any suitable support, as 34, and the movable member i^2 of the exhaust bellows i is connected to a similar stronger spring i^3 and is also connected by a link 35 to an actuating pneumatic s that is connected by a tube 36 to the aforementioned valve t .

40 The tone modulating chambers f and g are connected in parallel to the main chamber a , and between these modulating chambers, specifically between the chamber g and the extension f' of the chamber f are conduits A and B, leading to two groups of primary pneumatics of well known construction, and not illustrated. The conduits are under control of double valves y and z 45 respectively, that effect the distribution of wind of the desired tension to the groups of primary pneumatics through the conduits A and B.

50 The upper plates of these valves y and z , which control the admission of the stronger tension from the extension f' of the tension chamber f to the conduits A and B are freely movable on their spindles.

55 The valves y and z are controlled by the music sheet, and are operated by primary pneumatics w and x respectively, under the control of suitable double valves u and v respectively, the valve u controlling the primary pneumatic w through conduit 37, and 60 the valve v controlling the primary pneumatic x through the conduit 38. The valves u and v operate in connection with a tension chamber 39 connected to the main suction chamber a , or that is otherwise exhausted.

The valves u and v are similar to valves p q and t previously referred to, and are provided with tubes 40 and 41 connected to tracker bar T.

The operation is as follows:

70 When no special emphasis is desired, the wind produced by chambers f and g is weaker than that produced by the chamber a and the wind produced by the chamber f is as much weaker than that produced by the chamber g as the spring h^3 is weaker than the spring i^3 , because these springs, with the forces they exert, which as hereinbefore stated are different, act with different effect in opposition to the suction action in the 75 chambers f and g . Supposing the wind pressure produced by the chamber f were ten millimeters of mercury and that produced by the chamber g fifteen millimeters, all the notes operated from the chamber f would 80 have a tone strength corresponding to ten millimeters wind pressure and those actuated from the chamber g a tone strength corresponding to fifteen millimeters wind pressure. The wind pressure in chamber a 85 may be assumed as twenty millimeters.

90 If the valves p and q be opened for the purpose of exhausting or closing the controlling bellows part o , or if the hand lever 17 which forms a substitute for said bellows be correspondingly moved, the link l will move a maximum distance to the right in accordance with the movements of the bellows parts o and n . The valve c will therefore be moved in a direction to more 100 fully open and, by means of the transmission mechanism comprising link b^3 , lever b^2 and rod b' , the valve b will also be moved in its opening direction. The throttling bellows i and h will therefore be exhausted or 105 closed more nearly according to the movement of the corresponding valve. The exhaustion or closing of the throttling bellows additionally stresses the springs i^3 and h^3 , with the result that there is produced in 110 the two chambers f and g an increase of the vacuum corresponding to the additional stress placed upon the springs. Although the wind pressure produced by the two chambers f and g varies in itself, yet the 115 same ratio of such pressure will always be maintained in both of said chambers, as the springs h^3 and i^3 are of different strengths. With the exhaustion or collapsing of the two bellows h and i the two valves b and c will 120 be again simultaneously moved back to their original positions. It will be understood therefore that as the controlling bellows part o alone, or the bellows part n alone, or both bellows parts together, are operated by their valves p and q the movement of the two valves b and c , and consequently also the exhaustion or closing of the throttling bellows h and i and the stressing of the springs h^3 and i^3 on which the pressure in the two 125 130 135

chambers f and g is again dependent, will also be effected.

5 The primary pneumatics w and x which, through the valves y and z , control the distribution of the wind pressure to the different groups of notes, are always subjected to suction when the valves u and v are closed and are therefore then exhausted or closed, so that the valves y and z shut the chambers

10 g off from the conduits A and B.

If the valve u be opened, as shown, the primary pneumatic w will expand or open as atmospheric air flows therein through conduit 37 and the valve y will thereby be forced downward, this downward movement being assisted by the more powerful suction in the chamber g . The upper plate of the valve y will be drawn down by the vacuum in the chamber g and the chamber f will therefore be cut off from the chamber g . The valve y will then allow the group of notes or notes associated therewith through conduit A to play with the higher wind pressure produced by the chamber g , while 25 the other notes or group of notes associated with the valve v through conduit B are actuated by the wind pressure produced by the chamber f .

If the valve u be opened, the bellows x 30 will be filled with atmospheric air and the valve z will be operated in a similar manner to that described with reference to the valve y , so that the group of notes, or notes associated with this valve will be played with 35 the strength of the wind pressure produced by the chamber g .

If neither of the valves u or v be opened, then the valves y and z shut both of the conduits A and B off from the chamber g .

40 Owing to the vacuum in the chamber f the upper plates of the valves y and z , which are freely movable on their spindles, are seated so loosely that the group of notes or the notes associated with the valves y and z are nevertheless actuated by the wind produced 45 by the chamber f , as the chamber g is cut off from the chamber f and the conduits A and B by the lower plates of these valves which are drawn upward by the exhausted 50 or closed bellows w and x .

As has already been stated, the number of valves y and z is not limited to two, but depends on the number of the groups into which the notes are divided. A corresponding 55 arrangement may be provided for each individual note, if desired.

If it be desired to specially emphasize certain notes of those already emphasized and actuated by the wind pressure produced 60 by the chamber g this is effected by means of the valve t which controls the bellows s and is itself controlled from the tracker board T. Instead of employing the valve t , the bellows s may be controlled by a passage 65 opened or closed by the finger. Upon the

bellows s being exhausted or closed by any controlling mechanism the pull of the spring $\tilde{v}$ is thereby augmented. By this means the throttling bellows i will be powerfully exhausted, the valve b will thereby be more 70 widely opened and an increased wind pressure augmented by the suctional action of the bellows s will be instantly produced by the chamber g .

The notes actuated by wind pressure produced in the chamber g will therefore be instantaneously more heavily struck. The ratio of wind pressure produced in the chambers f and g will therefore at that instant be altered. The longer the valve t or 75 its equivalent can exert its action the more intense will be the emphasis.

In the construction of apparatus shown in Fig. 2 the action is substantially the same as that of the apparatus shown in Fig. 1, only 80 in this case the two throttling chambers f and g are not dependent upon each other, as in Fig. 1. The throttling action can therefore be varied as may be desired in each chamber. Each throttling chamber is 85 controlled by a corresponding unsymmetrical double bellows $n\ o$, and $n'\ o'$, respectively, and the throttling action depends on whether the bellows $n\ o$, or the bellows $n'\ o'$, works, or whether both bellows work together. 90

Special emphasizing bellows are provided for each chamber, namely the bellows s for the chamber g and the bellows s^a for the chamber f . Therefore with this apparatus 100 any desired notes or groups of notes may be specially emphasized from both chambers. The valves and other parts are in like manner duplicated. That is to say, both valve chests 26 and 26^a are connected through conduit 33 to chamber a and the valves are necessarily duplicated at $p' q'$ and t' with corresponding pipe connections 30^a, 31^a, and 32^a to the tracker bar, the duplicated parts being in most instances indicated by the 110 affix "a" to the reference character.

It will be noted that the construction is such that by the movement of the rod l the valve b or c and the bellows pertaining to the chamber controlled by said valve is operated oppositely to the pertaining bellows h or i , that is to say, when the valve c is opened by a pull on rod l the bellows i is collapsed, and vice versa; the bellows s however, opposes, when desired, the collapsing 115 of the bellows i . The same is true for both valves b and c and their pertaining mechanisms in both figures.

In Fig. 1, however, both bellows h and i are connected to the same lever h' , so that 120 in addition to the above statement the movement of one bellows will also be dependent upon the movement of the other, and thereby the tension in one tone chamber will vary to an extent with the tension in the other, 125 130

so that the ratio of the tensions in the two chambers remains substantially constant although the tension in one chamber varies.

I claim—

5. 1. Tone control mechanism for pneumatically actuated musical instruments, comprising a main suction chamber, a plurality of tone controlling chambers in which exist different tensions and connected in parallel 10 to said main suction chamber, a conduit arranged between the two chambers and means to admit the tension in one or the other tone control chambers to said conduit.
- 15 2. Tone control mechanism for pneumatically actuated musical instruments, comprising tone controlling chambers in which exist different tensions and connected to a conduit arranged between the chambers, means to connect the chambers singly and at will 20 to said conduit to admit the tension in said chamber that has been connected to said conduit, and means for each chamber to temporarily increase the tension therein and thereby accentuate the tone being played under the tension existing in the chamber for the time being and connected to said conduit.
- 25 3. Tone controlling mechanism for pneumatically actuated musical instruments, comprising a main suction chamber, tone controlling chambers connected thereto in parallel and in which exist different tensions, a valve in each chamber controlling the connection with the main chamber, note sheet controlled mechanism for actuating said valves, bellows for said tone controlling chambers maintained under different tensions, note sheet controlled means to increase the tensions of said bellows, a conduit arranged between the parallel connected chambers and means to singly connect said chambers and conduit.
- 30 4. Tone control mechanism for pneumatically operated musical instruments, comprising a main tension chamber, tone controlling chambers connected thereto, a valve controlling the connection of each chamber with the main chamber, a spring expanded bellows communicating with each tone controlling chamber, mechanism to simultaneously actuate the valve and bellows pertaining to a tone controlling chamber, a conduit arranged between the tone controlling chambers and means to singly connect said conduit and a tone controlling chamber.
- 35 5. Tone control mechanism for pneumatically operated musical instruments, comprising a main tension chamber, tone controlling chambers connected thereto, a valve controlling the connection of each chamber with the main chamber, a spring expanded bellows communicating with each tone controlling chamber, mechanism to simultaneously oppositely actuate the valve and bellows pertaining to a tone controlling chamber, means to retard the collapsing of said
- 40 bellows, a conduit arranged between the tone controlling chambers and means to singly connect said conduit and tone controlling chamber.
- 45 6. Tone control mechanism for pneumatically operated musical instruments, comprising a main tension chamber, tone controlling chambers independently connected thereto and having at different tensions, valves controlling the connection of said chambers with the main chamber, mechanisms to vary the tension in the individual tone controlling chambers, means interconnecting said mechanisms to maintain the ratio of the tensions in said chambers substantially constant, a conduit arranged between the tone controlling chambers, and means to singly connect said chambers and conduit at will.
- 50 7. Tone control mechanism for pneumatically operated musical instruments, comprising a main tension chamber, tone controlling chambers independently connected thereto and having at different tensions, valves controlling the connection of said chambers with the main chamber, mechanisms to vary the tension in the individual tone controlling chambers, means interconnecting said mechanisms to maintain the ratio of the tensions in said chambers substantially constant, a conduit arranged between the tone controlling chambers, means to singly connect said chambers and conduit at will, and means to increase the tension in one of said tone controlling chambers at will.
- 55 8. In emphasizing apparatus for a pneumatic player for a musical instrument, a main suction chamber, a number of throttling chambers, a throttle valve corresponding to each throttling chamber adapted to place the corresponding throttling chamber in communication with the main suction chamber, a tracker board, air conduits arranged between said throttling chambers, note sheet controlled valves to singly connect the throttling chambers with a conduit, lever mechanism connecting the throttle valves of said throttling chambers, bellows associated with said lever mechanism and in connection with said throttling chambers, springs connected to said bellows, and a controlling device connected to said bellows.
- 60 9. In emphasizing apparatus for a pneumatic player for a musical instrument, a main suction chamber, throttling chambers, a throttle valve for each throttling chamber controlling its communication with said main suction chamber, a tracker board, air conduits arranged between the throttling chambers, note sheet controlled valves to singly connect a throttling chamber and conduit, lever mechanism connecting said throttle valves, bellows associated with said lever mechanism and in connection with said

throttling chambers, springs connected to said bellows, controlling bellows controlled from said tracker board, and mechanism connecting said controlling bellows to said lever mechanism.

10. In emphasizing apparatus for a pneumatic player for a musical instrument, a main suction chamber, a number of throttling chambers, a throttle valve for each throttling chamber adapted to control the communication with said main suction chamber, a tracker board, air conduits arranged between the throttling chambers, note sheet controlled valves to singly connect a conduit and throttling chamber, lever mechanism connecting said throttle valves, bellows associated with said lever mechanism and in connection with said throttling chambers, springs connected to 20 said bellows, a controlling device connected to said bellows, and an independent controlling device corresponding to one of said throttling chambers.

11. Tone controlling mechanism for pneumatically operated musical instruments, 25 comprising a main tension chamber, throttling chambers under different tensions connected thereto, a throttle valve for each chamber, a conduit, means to singly connect, at will, one of said throttling chambers and 30 conduit, mechanism to manually or automatically actuate said throttle valves, a bellows associated with and connected to each throttling chamber, mechanism to maintain the ratio of tension between the 35 chambers substantially constant and mechanism to automatically increase the tension in one chamber.

In testimony whereof I have signed my name to this specification, in the presence 40 of two subscribing witnesses.

GUSTAV KARL HENNIG.
